UNITED STATES PATENT OFFICE.

CHARLES A. HAMMEL, OF LOS ANGELES, CALIFORNIA.

STEAM-BOILER.

973,111.

Specification of Letters Patent. Patented Oct. 18, 1910.

Application filed August 4, 1909. Serial No. 511,080.

To all whom it may concern:

Be it known that I, CHARLES A. HAMMEL, a citizen of the United States, residing at Los Angeles, in the county of Los Angeles and State of California, have invented new and useful Improvements in Steam-Boilers, of which the following is a specification.

My invention has relation to constructive improvements in those type of boilers, such as are illustrated and described in my U. S. Letters Patent No. 882,756 entitled "Oil burning steam boilers," and granted to me on the 24th day of March, 1908.

In the above mentioned patent the hydrocarbon burners were oppositely disposed, delivering their flames toward each other and having a single air admission means, while in this improved construction the burners are disposed so as to deliver their flames in the same general direction, thus enabling an operator to effectively control the heat generated thereby.

A main and important object of this invention is to arrange a novel disposition of the burners, whereby the maximum heat generated thereby will be directed to and absorbed by the rear portion of the boiler before the exhaust of the engine can force the gases through the flues to the atmosphere, thus greatly increasing the steaming efficiency of the boiler and utilizing in an economical manner the generated heat.

Another object of this invention is to provide constructive improvements, whereby a single burner may be operated to its fullest capacity without injury to the other burner.

A further object is to provide a construction, whereby I am enabled to effect a saving in fuel consumption, each burner being capable of operation independently of the other.

In the accomplishment of the above objects I preferably employ a plurality of burners, disposed so as to deliver their flames in the same general direction, without injury to each other, each being provided with an independent air admission means and a control means therefor.

In the annexed drawings forming a part of this specification, Figure 1— is central longitudinal section through the firebox of a locomotive boiler, illustrating an application of my invention. Fig. 2— is a transverse view taken on line 2—2 of Fig. 1. Fig. 3— is a central longitudinal section of a locomotive boiler illustrating a modified form of

my invention. Fig. 4— is a transverse view taken on line 3—3 of Fig. 3.

Referring more particularly to the drawings, the inside firebox or combustion chamber 5 is of the usual type, being closed at the top by crown sheet 6 and surrounded by a water jacket 7, the bottom of which is closed by the usual mud ring 8. The outside shell 9 of the firebox is connected to the waist 10, through which the tubes 11 pass from the tube sheet 12 to the smoke stack (not shown) at the front end of the boiler. Chamber 5 is closed at the bottom by a sheet or plate metal box, and corresponds in general form to the ash pan of locomotive boilers in which fuel of a solid type is consumed. Box 13 is provided with a metallic bottom plate 14 which extends from the rear end of the firebox forwardly approximately one-third of the length thereof, where it is bolted or otherwise secured to a vertically disposed plate 15 which extends upwardly from plate 14 and forms a bridge 16. Plate 17 which is bolted or otherwise secured to vertical plate 15 forms a closure for that part of the firebox that lies beyond plate 14. Plates 14 and 17 are provided with rectangular openings 18, 19, over which are mounted perforated castings 20 and 21, the upper faces of these castings lie flush with the top faces of the fire brick 22 with which the box 13 is preferably lined.

Secured to the under face of plates 14 and 17 are sheet metal air inlet boxes 23, 24, the rear vertical wall of each box being open to the atmosphere; and each provided with a damper 25, controlled from the cab of the engine in a suitable manner (not shown). By means of these air inlet boxes the admission of air through the perforated castings into the firebox may be satisfactorily and efficiently controlled. This method of taking the main air supply from the bottom through perforated castings is essentially the same in all respects as that construction described and illustrated in my heretofore mentioned patent, it preventing, as in that construction, the entrance of an excessive or undue amount of cold air to the combustion chamber, and at the same time retards the volume of air entering thereinto and enables the fireman of the locomotive to control the admission of air to the combustion chamber most effectively. The air as it enters through the perforations becomes highly heated from the operation of the burners and expands

that it will readily form a union with the gases that are being consumed within the combustion chamber. The entrance of air through the perforations in the bottom plates also tends to raise the burner flames and prevents dragging. It will be noted by an inspection of Fig. 1 of the drawings that the bulk of the air admitted to the combustion chamber is through inlet box 23, the inlet box 24 disposed under the flame projected by the forward burner being barely sufficient to supply that flame with the requisite amount of oxygen to start combustion.

The burners 26, 27 are mounted at the front and bridge walls of the firebox respectively, discharging their flames through air inlet openings *a* and *b* respectively toward the rear of the firebox, as clearly shown in Fig. 1 of the drawings. This disposition of the burners forms what I consider to be the novel and important feature of this construction, as by this disposition I am enabled to concentrate the heat produced by the flames of the burners in the rear portion of the firebox, so that that portion of the boiler that lies adjacent the rear of the firebox will absorb the maximum amount of heat delivered by the flames before the exhaust of the engine could force the gases through the flues to the atmosphere.

In Figs. 3 and 4 of the drawings I have illustrated a modified form of construction which is similar to the first described form in all essential particulars embodying only a change in the box construction. This form of box 27^a is provided with a metallic bottom plate 28, which extends from the rear end of the fire box forwardly to about the middle thereof. A short distance beyond the end of the plate 28 another plate 29 extends forwardly where it is bolted or otherwise secured to a vertically disposed plate 30 which extends upwardly from plate 29. The plates 28 and 29 are provided with rectangular openings 31, 32, over which are mounted perforated castings 33, 34, the upper face of the castings lying flush with the tops of the fire brick 35, with which the box 27^a is preferably lined. Secured to the under face of plates 28 and 29 are sheet metal air inlet boxes 36, 37, the rear vertical wall of each box being open to the atmosphere, and each provided with a damper 38, controlled from the cab of the engine in a suitable manner (not shown). The admission of air through the perforated castings into the fire box is exactly similar to the hereinbefore described construction, and the results are essentially the same as in the first described form. At the juncture of plates

28 and 29, in the center of the fire box, I have provided a centrally and transversely disposed bridge wall 39 having a pocket 40, which opens to the atmosphere at the bottom thereof. Mounted in pocket 40 is a burner 41, which discharges its flame toward the rear of the fire box through an air inlet opening 42 formed in one wall of the bridge 39. Vertically disposed plate 30 is provided with an air inlet opening 43, and mounted on the outside of this plate and adjacent to the opening 43 is a hydrocarbon burner 44 adapted to discharge its flame so as to impinge against one of the walls of the bridge 39. This construction, while not as efficient as the first described form, forces the heat to the rear of the fire box and accomplishes results that are highly satisfactory.

Having described my invention what I claim as new and desire to secure by Letters Patent is:—

1. The combination with a steam boiler having a firebox, provided with a transversely disposed bridge-wall, of means for delivering hydrocarbon flames from the front end of the firebox and the bridge-wall toward the rear end of the firebox, means for establishing a draft of air into the firebox adjacent the flame delivery means, a plurality of air admission means for admitting air directly into the firebox under each flame, one of said air admission means for each burner flame, and means located beneath each of said air admission means for controlling the volume of air to said admission means.

2. The combination with a steam boiler, of a firebox having a refractory lining on its bottom and sides, the bottom of said firebox being constructed so as to form a transversely disposed bridge-wall, a plurality of hydrocarbon burners disposed outside of said firebox, one at the forward end of the box and the other at the bridge-wall and both delivering the flames into the firebox toward the rear thereof, means for establishing a draft of air into the firebox adjacent the hydrocarbon burners, a plurality of air inlets in the bottom of said firebox, a metallic casing having an opening therein disposed under each of said air inlets, a closure for the opening in each casing, and means to control the closures.

In witness that I claim the foregoing I have hereunto subscribed my name this 27th day of July, 1909.

C. A. HAMMEL.
